WILLIAM F. BAMES, OF EDGEWOOD, PENNSYLVANIA, ASSIGNOR TO WESTINGHOUSE ELECTRIC & MANUFACTURING COMPANY, A CORPORATION OF PENNSYLVANIA

ELEVATOR CONTROL SYSTEM

Application filed January 25, 1928, Serial No. 249,274. Renewed December 17, 1930.

The invention relates generally to control systems and more particularly to systems for controlling the operation of electric elevators, hoists and other similar machinery.

5 In operating elevators of the variable-voltage type in places where the constant service is not required except at intervals throughout the day or the operation is very intermittent in character, such, for example, 10 as in apartment houses, it has been found very uneconomical to keep the motive means in continuous operation under its own power.

Since the driving motor for the generator 15 in variable-voltage and similar control systems must necessarily be of sufficient capacity for the ordinary operating load, its continuous operation, when the elevator is idle for long periods of time, results in lowering the power factor of the supply circuit, which, for well-known reasons, is very undesirable. Furthermore, the no-load losses of a large motor, extending over a considerable length of time, become quite 25 appreciable when compared with the useful power consumed.

The object of the invention, generally stated, is to provide a control system for electric elevators which shall permit economical operation under intermittent operating conditions.

A more specific object of the invention is to provide, in a variable-voltage elevator control system, an auxiliary motor for driving 35 the motor-generator set at a speed corresponding to its normal operating speed, to permit the main motor to be disconnected from the supply line during such time as the elevator is idle.

40 A further object of the invention is to provide for reducing the no-load power losses of an intermittently operated electric-elevator system.

45 Another object of the invention is to provide for increasing the average power factor of an intermittently operated electric-elevator system.

Other objects of the invention will be 50 become evident from the following descrip-

tion, taken in conjunction with the accompanying drawings, in which

Figure 1 is a diagrammatic view of a variable-voltage elevator-control system embodying my invention, and

Fig. 2 is a diagrammatic view of an electrical machine which may be utilized to provide a modification of the system shown in Fig. 1.

Referring to Fig. 1, the control system therein shown is suitable for operating a single elevator. As shown, the elevator system comprises an elevator car C, suspended in a hatchway by means of a hoisting cable Ca which passes over a hoisting drum D to a suitable counterweight CW, in the usual manner.

The hoisting drum D may be driven in any suitable manner and, as illustrated, is directly coupled to an elevator motor EM having an armature EM' and separately excited shunt field winding EMF.

As shown, the control for the elevator motor EM is of the variable-voltage or Ward-Leonard type, wherein a motor-generator set, comprising a direct-current generator G and main driving motor M, is provided. The generator G is of the variable-voltage compound-wound type having an armature G', a series field winding GSF, a shunt field winding GF and a demagnetizing field winding GAF. The armature G' is arranged to be connected in "loop" circuit with the armature EM' of the elevator motor EM.

The main driving motor of the motor-generator set may be of any suitable type and, as illustrated in this particular embodiment of the invention, the squirrel-cage induction motor M, having a stator winding MS and a squirrel cage rotor M', is provided. As shown, the rotor M' is directly connected to the armature G'.

In order to provide a direct-current source of excitation for the field windings of the generator G and elevator motor EM and to operate the various control switches, a direct-current exciter E, having a shunt field winding EF and armature E' is utilized.

The elevator motor EM is controlled, in the usual manner, through the agency of a car switch CS on the car C, the usual "up" and "down" direction switches, designated 5 as 1 and 2, respectively, a motor-circuit control switch 3 and a speed switch 4.

In the operation of an elevator-control system of this type, it is the usual practice to continuously operate the motor-generator set, which supplies power to the elevator motor, from the power derived from the main motor M. However, in this particular embodiment of the invention, an auxiliary motor AM is provided to cooperate with the 10 main driving motor M in a manner which will be described in detail hereinafter.

In order that a more comprehensive understanding of the invention may be obtained, a description of the operation of the 15 system, when operating in accordance with the present invention, will now be given.

In order to provide power for operating the elevator, the motor-generator set, comprising the motor M and generator G, must 20 first be set in operation. The motor-generator set may be started in operation by actuating a switch 5 to the closed position, which establishes an operating circuit for the auxiliary motor-line switch 6 extending 25 from the conductor L1 of the multi-phase power supply comprising the conductors L1, L2, L3, through conductor 7, operating coil of the line switch 6, conductor 8 and switch 5, to line conductor L2.

Upon closure of the auxiliary motor-control switch 6, a multiphase energizing circuit is established for the auxiliary motor AM, one phase of which may be traced from the line conductor L1, through conductors 30 7 and 9, contact members *a* of the switch 6, conductor 11, resistor 12 and conductor 13 to one phase of the stator winding AMS: a second phase extends from the line conductor L2, through switch 5, conductors 8 35 and 14, contact member *b* of the switch 6, conductor 15, resistor 16 and conductor 17 to a second phase winding of the stator AMS, and a third phase extending from the line conductor L3, through conductor 18, 40 contact member *c* of the switch 6, conductor 19, resistor 21 and conductor 22 to the third phase winding of the stator AMS. The resistors 12, 16 and 21 are included in the auxiliary motor circuit, as described, to permit 45 the auxiliary motor AM to accelerate to full speed without drawing excessive current from the line. As will be observed, a short-circuiting switch 23 is provided for short-circuiting the resistors 12, 16 and 21 from 50 the auxiliary motor circuit after a certain predetermined time. The particular switch, as illustrated, is provided with an actuating coil 24 and a dash-pot 25 and operates in a well-known manner, in which the actuating 55 coil 24 becomes energized as soon as the

motor circuit is completed, but the closure of the contact members is retarded by the action of the dash pot 25.

Assuming the elevator to be at the first floor, the attendant on the car may start the car upwardly by actuating the handle 26 of the car switch CS to the first point in the left position, as viewed in the drawing, thereby bridging the contact fingers 28 and 29 and completing an operating circuit for the "up" direction switch 1 extending from line conductor L4, through conductor 27, contact members 28 and 29 bridged by the movable segment 31, conductor 32, operating coil of the switch 1, normally closed contact members *a* of the "down" direction switch 2, conductors 33 and 34, operating coil of the switch 3, and conductors 35 and 36 to the line conductor L5.

The "up" direction switch 1 closes its 85 contact members *b* and *c*, thereby supplying the generator shunt field winding GF with exciting current in one direction through a circuit which extends from line conductor L4, through conductor 37, contact members 90 *c* of the "up" direction switch 1, conductor 38, field resistor 39, field winding GF, contact members *b* of the "up" direction switch 1, and conductors 41 and 36 to the line conductor L5.

Simultaneously with the closure of the "up" direction switch 1, the contact members *a* of the elevator motor switch 3 are closed to connect the armature G' of the generator G in "loop" circuit with the elevator motor armature EM', as shown. However, since motive power other than from the auxiliary motor AM is now required for operating the generator, the switch 3 is provided with contact members *b* which are 100 also simultaneously actuated to the closed position to establish an operating circuit for the main line switch 43 of the main motor M. As shown, the switch operating circuit extends from the energized conductor 8 through the operating coil of the switch 43, conductor 44, contact members *b* of the switch 3 and conductor 7 to the line conductor L1. Upon the closure of the line switch 43, the stator winding MS of the motor M is connected to the multi-phase power supply from the energized conductors 9, 14 and 18, through the contact members *a*, *b* and *c* of the switch 43 and conductors 45, 46 and 47, as shown.

In order to accelerate the elevator to full speed, the car switch CS is actuated to the second position, where the movable contact member 31 engages the contact finger 48, thereby completing an operating circuit for the speed switch 4, which, as shown, is disposed to short circuit the resistor 39 in series with the generator shunt field GS. The operating circuit for the speed switch 4 may be traced from the line conductor L4, 130

through conductor 27, contact members 28 and 48 bridged by the movable segment 31, conductor 49, operating coil of the speed switch 4, and conductors 50, 41 and 36 to line conductors L5.

It will be readily understood that, upon the closure of the switch 4, the exciting current of the generator G is increased, causing the generator G to develop a higher voltage to cause the consequent acceleration of the elevator EM.

The operation of the elevator at full speed in the up direction may be continued until the operating handle 26 of the car switch CS is notched back to the first position, whereupon, the operating circuit for the speed switch 4 is interrupted, which inserts the resistor 39 in the generator-field circuit, thereby automatically decelerating the elevator motor EM. Upon further movement of the car switch to its initial or "off" position, the "up" direction switch 1 and switch 3 are deenergized and, therefore, open to deenergize the generator shunt field circuit and disconnect the motor M from the power supply.

Since it is desirable to demagnetize the generator field as quickly as possible, in order to bring the elevator motor to rest quickly and efficiently, the generator-demagnetizing winding GAF is disposed to become energized upon the opening of the "up" direction switch 1. In this event, a circuit is established from one terminal of the armature G' through the field winding GSF, demagnetizing winding GAF, conductor 52, contact members d of the "down" direction switch 2, contact members d of the "up" direction switch 1, conductors 53 and 54 to the opposite terminal of the generator armature G'. The effect of this winding is to quickly reduce the magnetism in the generator field, thus preventing the building up of a strong field under the influence of residual magnetism in the field, aided by the strong series field winding GSF, and thus prevent "creeping" of the motor through the brake (not shown) after exciting current is no longer supplied to the separately excited field winding GF.

It will be observed that the operation of the auxiliary motor AM is completely controlled by the switch 5 and, therefore, the operation of the main control apparatus does not affect the operation of the auxiliary motor AM which continues to drive the motor-generator set and the exciter E at a speed corresponding to its normal operating speed.

It will be readily understood that the operation of the system is such that the driving motor M of the motor-generator set may be successively energized and deenergized in accordance with the operation of the elevator, since the rotating parts are constantly

in operation at substantially their normal operating speed.

In the event that it is undesirable to use a separate auxiliary motor AM and a separate exciter E, a combination machine, such, for example, as illustrated in Fig. 2, may be utilized in their place. It will be observed that the particular piece of apparatus, as illustrated, comprises a rotatable armature 55 provided, at one end, with a commutator-and-brush assembly 56 and, at the other end, with a plurality of slip rings 57, in a manner which is ordinarily used in the construction of rotary converters. A shunt field winding 58 is wound upon the usual type of field poles and a squirrel-cage winding 59 is wound in the pole faces as shown.

It will be readily understood that, in utilizing a combination exciter and auxiliary motor of this type, the machine, upon becoming energized on the three-phase side, through the slip rings 57, starts as a squirrel-cage induction motor. As the speed of the armature 55 increases, a direct-current voltage is developed which automatically energizes the shunt field winding 58, the machine operates as a synchronous motor from the alternating-current side.

Since the full-load speed of the driving motor M of the motor-generator set would, in this case, be less than the synchronous speed of the combination motor and exciter, provision must be made to disconnect the latter from the supply source whenever the motor M is energized. In this particular embodiment of the invention, the motor switch 43 is provided with additional contact members D, E and F, which are normally closed and, therefore, interrupt the power circuit to the combination motor and exciter whenever the switch 43 is operated to its closed position to connect the main motor M to the supply source.

It has not been deemed necessary to describe the operation of the system when the elevator is travelling in the "down" direction, it being obvious that the operation is the same, with the exception that the "down" direction switch 2 is energized instead of the "up" direction switch 1.

It will be readily understood that either embodiment of the invention may be readily applied to any elevator-control system of this type wherein a motor-generator set is utilized for supplying power to the elevator motor, and it is particularly advantageous where only intermittent operation of the elevator is desired and where heavy penalties are imposed upon the power user for permitting his system to operate at a low or undesirable power factor.

The described embodiments of my invention being merely illustrative, I do not desire to be limited to the exact details of

the apparatus disclosed, except as they are defined in the appended claims.

I claim as my invention:

1. In an elevator control system, in combination, an elevator, a motor for operating the elevator, controlling means for starting and stopping said elevator motor, a generator for supplying power to said elevator motor, a motor for driving the generator when the elevator is in operation, a power supply for said motor, means operably responsive to actuation of the control means to start said motor for connecting said driving motor to the power source and means operable to maintain the driving motor and generator in operation when said motor has been disconnected from the power supply.
2. In an elevator control system, in combination, an elevator, a motor for operating the elevator, control means for starting and stopping said elevator motor, a generator for supplying power to said elevator motor, a main drive of sufficient power to operate said generator when the elevator motor is fully loaded, an auxiliary drive of less power for operating the generator when said elevator motor is idle, and means operably responsive to actuation of said control means to start said elevator motor for starting said main drive.
3. In an elevator control system, in combination, an elevator, a motor for operating the elevator, a motor-generator set for supplying power to said elevator motor, an auxiliary motor for starting the motor-generator set, a power supply, a switch for connecting the auxiliary motor to the power supply, an elevator control switch, electromagnetic means responsive to said control switch for connecting the generator to the elevator motor, and electromagnetic means controlled by the elevator control switch for connecting the driving motor of the motor-generator set to the power supply.
4. In an elevator control system, in combination, an elevator, a motor provided with a field winding for operating the elevator, a motor-generator set for supplying power to the elevator motor, said set comprising a direct-current generator provided with a field winding and an alternating-current induction motor disposed to drive the generators, a power source for the motor-generator set, means for controlling the operation of the elevator motor, said means being disposed to alternately connect and disconnect the alternating-current motor and the source of supply when the elevator is operated, and means for exciting the field windings of the elevator motor and generator, said means being operable to drive the motor-generator set when the main motor is disconnected from the power supply.
5. In an elevator control system, in com-

bination, an elevator, a motor provided with a field winding for operating the elevator, a motor-generator set for supplying power to the elevator motor, said set comprising a direct-current generator provided with a field winding and an alternating-current induction motor disposed to drive the generator, a power source for the motor-generator set, means for controlling the operation of the elevator motor, said means being disposed to alternately connect and disconnect the alternating-current motor and the source of supply when the elevator is operated, and a combination motor and exciter, said motor and exciter comprising a generator element for exciting the field windings of the motor and generator and a motor element disposed to drive the motor-generator set when the alternating-current driving motor is disconnected from the power source.

6. In a control system for an elevator car, a source of power for said system, a work motor for operating said elevator, a generator for supplying power to said work motor, a motor for driving said generator, a second motor for driving said generator, switching mechanism for connecting one of said motors to said source, control mechanism operable to cause said work motor to start said elevator, and means adapted after operation of said control mechanism to connect the other of said motors to said source.

7. In a control system for an elevator, a source of power for said system; motive means for said elevator comprising a work motor for operating said elevator, a generator for supplying power to said work motor, a main motor for driving said generator, and an auxiliary motor for driving said generator; and a controller for said motive means including switching mechanism operable to cause connection of said auxiliary motor to said source of power, control mechanism operable to cause said work motor to start said elevator, and means responsive to operation of said control mechanism to connect said main motor to said source of power.

8. In a control system for an elevator car, a source of power for said system, a work motor for operating said elevator, a generator for supplying power to said work motor, a main motor for driving said generator, an auxiliary motor for driving said generator, switching mechanism for connecting said auxiliary motor to said source, control mechanism operable to cause said work motor to start said elevator, and means responsive to operation of said control mechanism for connecting said main motor to said source, said last named means being effective regardless of the load supplied said work motor by said generator.

9. In a control system for an elevator, a power supply for said system, a work motor

- for operating said elevator, a generator for supplying power to said work motor, a main motor for driving said generator, an auxiliary motor for driving said generator, and a controller for said system, said controller including a switch movable from an initial position to a second position, switching mechanism adapted while said switch is in said initial position to connect said auxiliary motor to said source of power, starting mechanism rendered effective upon movement of said switch to said second position to cause said work motor to start said elevator, and means also rendered effective upon movement of said switch to said second position for connecting said main motor to said source and for disconnecting said auxiliary motor from said source. 6 70
- 10 11. In a control system for an elevator, a work motor for operating said elevator, a generator for supplying power to said work motor, a main motor for driving said generator, control circuits and mechanism for controlling said circuits including a switch 75 movable from an initial to a starting position to cause said work motor to start said elevator, and an auxiliary dynamo electric machine adapted while said switch is in said initial position to operate as a motor and drive said generator, and adapted while said elevator is in operation to operate as a generator and supply power for said control mechanism. 15 80
- 20 12. In a control system for an elevator, a main source of power for said system, a direct current work motor for operating said elevator, a direct current generator for supplying power to said work motor, said generator having a shaft, a main motor for 85 driving said generator, control circuits and mechanism for controlling said circuits including a switch having an initial and a car starting position, and means for maintaining said generator in rotation while said 90 switch is in said initial position and for supplying direct current for said control mechanism comprising a translating device, connections between said main power supply and said translating device and between said control circuits and said translating device, and means for mechanically connecting said translating device to said generator shaft. 95
- 25 13. In a control system for an elevator, a source of alternating current supply, a direct current work motor for operating said elevator, a direct current generator for supplying power to said work motor, said generator having a shaft, a main alternating current motor for driving said generator, control circuits and mechanism for controlling said circuits including a switch having an initial and a car starting position, and means for maintaining said generator in rotation while said switch is in said initial position and for supplying direct current for said control mechanism comprising a translating device, connections between said alternating current source and said translating device and between said control circuits and said translating device, and means for mechanically connecting said translating device to said generator shaft. 100
- 30 14. In a control system for an elevator, a source of alternating current supply, a direct current work motor for operating said elevator, a direct current generator for supplying power to said work motor, said generator having a shaft, a main alternating current motor for driving said generator, control circuits and mechanism for controlling said circuits including a switch having an initial and a car starting position, means for maintaining said generator in rotation while said switch is in said initial position and for supplying direct current for said control mechanism comprising a translating device, connections between said alternating current source and said translating device and between said control circuits and said translating device, means for mechanically connecting said translating device to said generator shaft, and means responsive to movement of said switch to said car starting position for connecting said main driving motor to said alternating current source and for interrupting the connections between said translating device and said alternating current source. 105 110
- 35 15. In a control system for an elevator, a source of alternating current for said system, a direct current work motor for operating said elevator, a direct current generator for supplying power to said work motor, said generator having a shaft, a controller for said system including control apparatus and circuits associated therewith, and means for driving said generator and for supplying direct current for said control apparatus, said means comprising a translating device, connections between said translating de- 115 120
